UNITED STATES PATENT OFFICE.

WILLIAM ASHERT, OF DES MOINES, IOWA.

DETACHABLE TOOL-HANDLE.

SPECIFICATION forming part of Letters Patent No. 784,772, dated March 14, 1905.

Application filed April 11, 1904. Serial No. 202,571.

To all whom it may concern:

Be it known that I, WILLIAM ASHERT, a citizen of the United States, residing at Des Moines, in the county of Polk and State of 5 Iowa, have invented certain new and useful Improvements in Detachable Tool-Handles, of which the following is a specification.

The object of my invention is to provide a tool and handle in which the handle may be 10 readily, quickly, and easily attached to the tool and firmly held in position therein and readily adjusted to take up wear between the handle and the tool-eye.

My invention consists in certain details in 15 the construction, arrangement, and combination of the various parts of the device, whereby the objects contemplated are attained, as hereinafter more fully set forth, pointed out in my claims, and illustrated in the accompanying drawings, in which—

Figure 1 shows a perspective view of a tool with my improved handle applied thereto. Fig. 2 shows a longitudinal central sectional view of the tool and the adjacent portion of 25 the handle. Fig. 3 shows a like view with the handle projected farther through the tool-eye, and Fig. 4 shows a transverse sectional view through the center of the tool and the adjacent portion of the handle.

Referring to the accompanying drawings, I have used the reference-numeral 10 to indicate the tool. In the accompanying drawings I have shown a miner's pick as the tool to be applied to the handle, it being understood that the handle is designed to apply to any similar tool. At the center of the tool is a handle-eye tapered from the lower to the upper surface of the tool, said handle-eye being oblong in shape. Near the top of the tool I have formed in the 35 side walls thereof adjoining the handle-eye two notches to receive a cross-piece 11. These notches do not extend outwardly through the side walls of the tool. They simply form a rest to receive the cross-piece 11, so that its top may be flush with the top of the tool. The said cross-piece is provided with a central opening designed to receive a screw-threaded rod 12, having a head 13, the said head capable of entering the cross-piece, so 45 that its top is flush with the top of the cross-

piece. Formed in the center of the head 13 is an angular recess 14, designed to receive an angular wrench by which the screw-threaded rod may be turned.

The reference-numeral 15 indicates the body portion of the handle-socket. This body portion is preferably formed solid and may be of cast metal. Its exterior is tapered to accurately fit the handle-eye of the tool. At its outer end is a transverse notch 16, designed 60 to admit the cross-piece 13 when the handle-socket is projected partly through the handle-eye of the tool. The outer surface of its lower end is tapered downwardly and inwardly and formed hollow to receive a wooden 65 handle 17, which may be secured to the socket by the bolt 18. In the end of the wooden handle I have provided an opening 19 to receive the screw-threaded rod 12, as shown in Fig. 4.

In practical use it is only necessary to provide a single handle with a large number of tools, and assuming that the tools used in connection with the handle were miners' picks the metal of which the tool proper is composed must be a relatively high-grade 75 steel and the only parts of this steel that are subjected to excessive use and wear are the points, and yet there must be a certain weight given to the combined tool and handle to 80 make the pick effective, and it is important in tools of this kind that the weight be almost wholly contained within the tool proper. For this reason I provide the tool proper with a handle-eye of relatively large size, so 85 that there is little steel in the tool itself. I then form the socket-body to fit the interior of the handle-eye and form the said socket-body solid and so arrange the socket-body that the solid heavy portion thereof lies almost wholly within the handle-eye. In order to firmly secure the handle-socket in the tool, I place the cross-piece 11 in the shoulders provided for it at the sides of the handle-eye, and I then pass the screw-threaded bolt 12 90 through the opening in the cross-piece and into and through the body portion of handle-socket, which is screw-threaded to receive the said rod. When the rod 12 is turned as far 95 as possible, the handle-socket will be firmly 100

secured to the tool and none of the parts of the fastening devices will project beyond the surface of the tool where they might be likely to be marred or broken. When it is desired 5 to substitute a new tool on the handle, the operator inserts an angular wrench in the angular opening 14 of the rod 12 and loosens the rod far enough so that the cross-piece 11 may be elevated out of the shoulders provided 10 for it and turned to position longitudinally of the handle-eye, whereupon the tool may be detached and a new one substituted. Assuming that the socket-body portion does not fit the handle-eye of the new tool in the same 15 way as the tool which is removed, then the operator may by turning the screw-threaded rod 12 far enough draw the handle-socket-body portion farther up through the handle-eye until an accurate fit is obtained, as shown 20 in Fig. 4.

Obviously none of the parts of the attaching devices are exposed to wear or breakage and the major portion of the weight of the handle-socket body is contained directly in 25 line with the longitudinal center of the tool, as required for effective work.

Having thus described my invention, what I claim, and desire to secure by Letters Patent of the United States therefor, is—

30 1. The combination with a tool having a handle-eye and also having notches adjacent to the upper end of the handle-eye, of a cross-piece resting in said notches and formed with a central opening, a handle-socket having a 35 body portion introduced into the handle-eye,

said body portion formed with a notch at its upper end to receive said cross-piece and a screw-threaded rod passed through the cross-piece and seated in the socket.

2. The combination with a tool having a 40 handle-eye tapered from its lower to its upper end, of a cross-piece at the upper end of the handle-eye resting on the tool-head, a handle-socket having a solid body portion tapered to fit the handle-eye and susceptible of 45 projecting above the top of a tool-head having a handle-eye of sufficient size and formed with a notch to receive the cross-piece, and a screw-threaded rod mounted in the cross-piece and seated in the body portion of the socket. 50

3. The combination with a tool formed with a handle-eye tapered from its upper to its lower end and also formed with notches in the sides of the top portion of the tool adjacent to the handle-eye, of a cross-piece resting in 55 said notches and formed with a central opening, a handle-socket formed with a solid body portion tapered to fit the handle-eye and formed with a transverse notch at its upper end to receive said cross-piece, a handle secured in the socket and a headed screw-threaded rod passed through the cross-piece through the notch in the top of the handle-socket and seated in the handle-socket, said 60 rod formed with an angular opening in its head.
